UNITED STATES PATENT OFFICE.

ELsie BROWN, OF BUFFALO, NEW YORK.

PLEASURE CAR.

Application filed January 28, 1927. Serial No. 164,274.

My present invention has reference to an amusement device of the type known as merry-go-rounds and carrousels employed in parks, at fairs and the like.

5 An object is the provision of an amusement device of this character in which the parts constituting the same may be readily disconnected and folded in a small package for storage or transportation but which 10 when in set up condition will afford a strong and rigid structure.

A further object is the provision of an amusement device of this character that shall present an ornamental appearance and 15 constructed to represent the coach, or rather a plurality of connected coaches, employed by Cinderella in the fairy story, the device being mounted on wheels which travel on a circular track and being operated by a motor 20 which is suitably controlled, there being also associated with the device a musical instrument which is operated simultaneously with the device, and there being also means for injecting a continuous blast of air 25 through the bottom of the coach compartments which will afford both surprise and amusement to the occupants thereof as well as effectively ventilating such compartments.

A further object is the construction of an 30 amusement device of this type in which a hollow shaft is mounted for rotation upon a stationary post or axle, the said shaft having a hub from which radiate the movably connected spokes, the outer ends of the 35 spokes being formed with spindles for the traction wheels and the latter travel on a circular track, the spokes at their outer ends and inward thereof having uprights secured thereto and partitions, including floors and 40 ceilings are connected to these uprights, to divide the device into a plurality of compartments, access to which being obtained through suitable doors, while the top for the device comprises a fabric whose outer edge 45 is lapped over a ring member secured to the outer uprights, and in which adjustable and flexible means between the said outer posts and the hollow shaft support the top, there being means for revolving the shaft, means 50 for operating a musical instrument during the turning of the device and means for injecting a blast of air through the bottom of the compartments when the device is operated, the volume of air being comparatively 55 small at the starting of the device but increasing as the device is rotated.

To the attainment of the above broadly stated objects and many others which will present themselves as the nature of the invention is better understood, the improvement also resides in certain other novel features of construction, combination and operative association of parts, one satisfactory embodiment of which is disclosed by the accompanying drawings.

In the drawings:

Figure 1 is a side elevation of my improvement.

Figure 2 is a top plan view thereof, with the cover removed, and with parts in section.

Figure 3 is a sectional view approximately on the line 3-3 of Figure 2.

Figure 4 is a sectional view approximately on the line 4-4 of Figure 2.

Figure 5 is a side elevation of the hub for the hollow shaft.

Figure 6 is a sectional view on the line 6-6 of Figure 7.

Figure 7 is a sectional view on the line 7-7 of Figure 6.

Figure 8 is a detail sectional view on the line 8-8 of Figure 6.

Figure 9 is a side elevation of the collector ring.

Figure 10 is a detail sectional view on the line 10-10 of Figure 4.

In carrying out my invention I employ a hollow metal base 1 that has on its lower edge an outstanding flange 2 which rests on the ground on which the improvement is erected. The base has a central tubular socket portion 3 which projects beyond the flange 2 so that the lower end thereof is embedded in the ground. The second end 95 has a squared bore for the reception of the squared end 4 of the cross sectionally rounded post or axle 5.

Arranged over the axle 5 and rotatable therearound there is a tubular shaft 6. This 100 shaft has fixed adjacent to its lower end a hub 7. The hub is arranged directly over the flat top of the base 1, and the confronting faces of the hub and base are provided with race-ways for anti-frictional elements 8.

The hub from its outer face has equi-distantly spaced T-shaped sockets 9 therein. In each of these sockets there is designed to be received cross sectionally T-shaped spokes 10, removable means 11 passing 110 through the hub and effectively sustaining the spokes in the sockets. The spokes 10,

of course, radiate from the hub and are of an equal length. Each spoke preferably has its web portion, at its outer end thickened, as at 11', (Figure 7), and extending from these 5 thickened ends there are spindles 12 on each of which there is journaled a wheel 13. The wheels travel on a circular track 14. Except for the wheels, all of the elements above described are of metal and are associated for 10 easy separation. The wheels 13 are, of course, held on their spindles by the usual nuts.

Each spoke, on its upper face, at and inward of its outer end has removably fixed 15 thereto angle brackets 15 and 16, respectively. The upstanding flanges of the brackets 15 and 16 are received in cross sectionally U-shaped metal members, the outer members and posts being indicated by the numerals 20 17 and the inner members by the numerals 18. To the sides of the posts 17 and 18 there are secured partition plates 19, and below the partition plates there are supported on the spokes floor plates 20. To 25 the ends of the partition plates 19 there are secured the flanged ends of plates 21 and 22 that provide the front and rear of the compartments 23 of the device. The outer or front plates of the compartments are provided with window openings 24 and with a door opening between said window openings, the last mentioned opening being normally closed by a hinged door 25 having suitable latching means 26. It is to be noted 30 that the removable means, preferably in the nature of nuts and bolts that connect the posts 17 and 18 to the partitions 19 likewise connect the front and inner plates 21 and 22 with the partition plates, so that the compartments of the device can be easily and 35 quickly set up. The compartments 23 are each covered by a top, the same being preferably in the nature of an upwardly bulged or arched plate 27, the edges of the top 40 plates being flanged downwardly and secured by removable brackets 28 to the walls of the compartments. In each compartment, at the ends thereof, there are seats 29 for the occupants, and each compartment has its 45 bottom or floor centrally formed with an opening surrounded by a depending box-like casing 30, the latter being provided with an apertured top 31. The inner posts 18 are of the same length, but these posts are of a 50 less length than the outer posts 17. These posts 17, adjacent to the upper ends thereof, are braced by a metal band. The band is made up of segments 32 that have flanged 55 ends 33 that rest against the sides of the posts 17, and are secured thereon by removable means 34. Opposite the band there is 60 removably secured on each post an ornamented plate 35 shaped to represent a shield, there being spacing means 26 between the 65 shield 35 and the post.

The axle 5 extends a slight but suitable distance above the hollow shaft 6 and has fixed on its upper end a staff for a flag or pennant. The top of the hollow shaft 6 is formed or provided with a downwardly extending outwardly flared cap 37 and below the cap there is fixed on the shaft 6 a ring or band 38. The band 38 is provided on its periphery with spaced ears 39, and to each of these ears there is connected either a rod, 70 wire or like elements 40. The outer ends of each element 40 is connected to the top of one of the posts 17. The elements 40 are adjustable and may have associated therewith turn-buckles 41 for accomplishing such 75 adjustment so that the said elements will be retained taut when the device is set up.

Arranged beneath and if desired removably secured to the outer face of the cap 37, and resting on the elements 40 there is the 80 canvas top 41' of the improvement. The top is made up of segmental strips which have their edges stitched together, and the outer and widened ends of these strips have stitched or otherwise secured thereon a band-like extension 42. This extension or what may be properly termed the flange of the top 85 is received beneath the shields 35 and has passed therethrough the securing means 43 that hold the shields on the posts 17.

The band 32 has preferably painted thereon scenes from the fairy story Cinderella and the outer plates or panels of the several compartments including the doors and windows thereof are ornamented to simulate 100 the well known pictorial illustrations of the coach supposed to have been occupied by the said Cinderella in the said fairy story. In addition to this there is removably secured to the outer face of the device arched guards 105 44 for the wheels 13, and steps 45 opposite the said doors 25, the said steps being arranged between the guards 44.

As far as the description has progressed it will be noted that I have provided a comparatively cheap construction which is highly ornamental and inviting to the pleasure seeking public. It will be further noted that all of the constructions comprise removably associated parts which are of metal, with 110 the exception of the canvas top of the improvement.

Removably fixed on the under face of the spokes 10 there is a grooved wheel 46, the said wheel being preferably provided with 115 outwardly extending arms for additional and removable securing means. The wheel is really in the nature of a ring and surrounds the base 1. The wheel has trained in the groove thereof an endless belt 47. This belt has its leads directed around guide wheels 48 and also around a drive wheel 49. The drive wheel 49 has fixed thereon a gear ring 50, and this ring is in mesh with a pinion 51 on the shaft of a motor 52. In 120 125 130

the showing of the drawings the motor is electrically operated and is controlled by a switch 53. The operation of the motor will, of course, revolve the device.

5 Removably supported on two of the spokes there is a plate 54, and mounted on this plate there is a motor 55 which operates a blower 56 of the ordinary construction. The outlet for the blower casing communicates with a circular pipe 57. The pipe 57 is preferably made up of sections, and the said sections being connected together by T-couplings 58 and the angle branches of these couplings have attached thereto pipe members 59 that lead respectively into each of the casings 30. The pipe 57 is suitably supported on the spokes.

20 Between another pair of spokes there is secured a plate 60 that supports thereon a musical instrument, such as an organ 61. The musical instrument is operated by a motor 62.

25 The motors 55 and 62 are, in the showing of the drawings, electrically operated, and, therefore, I removably but fixedly secure around the lower portion of the hub 7 an insulator ring 63. On the outer face of this ring there is fixed copper collector rings 64. These rings are arranged in spaced pairs and suitably supported between the spokes there are branches 65—65 66—66 that are wired, respectively to the motors 55 and 62. Also supported between the pairs of spokes there are branches 67—67 and 68—68 that 30 contact with the respective pairs of collector rings, and to these branches there are connected the conductors from a battery or like source of power 68. The conductors from the branches 67 and 68 are in the same source of power and one of each of said conductors terminates in a contact element that is engageable by switches 69 or 70. The battery 68 is also wired to the motor 55.

35 It will be apparent that by closing the circuit for the motor 52 the device will be caused to travel in a circular path on the track 14. By closing the switch 70 the motor 62 will be thrown into operation so that the musical instrument 61 will be sounded. By closing the circuit to the motor 55 the blower will be actuated. The blower will force air into the casing 30 and from thence through the apertured top 31 for the said casings so that the occupants of

55 the compartment will be subjected to a continuous blast of air which will occasion both surprise and amusement, such air also effectively ventilating the several compartments.

60 The simplicity of my construction and the novelty thereof will, it is thought, be perfectly understood and appreciated by those skilled in the art to which the invention relates when the foregoing description has been carefully read in connection with the accompanying drawings. Of course, I do not wish to be restricted to the precise details of construction herein disclosed and, therefore, it is to be understood that I hold myself entitled to make such changes therefrom as fairly fall within the scope of what I claim.

65 Having described the invention, I claim:—

70 In a merry-go-round, a central base resting on the ground, an axle removably supported therein and arising therefrom, a hollow shaft surrounding the axle, a hub on the shaft, above the base, anti-frictional bearings between the hub and base, removable spokes radiating from the hub, ground 75 wheels journaled on the outer ends of the spokes, removably secured inner and outer uprights on the spokes, removable plates secured to the opposite faces and ends of the posts and providing compartments therebetween, floor plates for the compartments supported on the spokes, and a removable top for each compartment, a sectional ring secured to the outer posts, a downwardly flared cap on the outer and upper end of the 80 hollow shaft, a ring member on the shaft below said cap, adjustable and flexible means secured to the ring member and to the outer posts, a fabric cover supported on the flexible elements having its inner end arranged between the cap and its outer end flanged and disposed over the sectional ring, removable plates securing the flange of the cover to the post, means for revolving the hollow shaft and the elements connected therewith, control means for said operating means, means for injecting a blast of air into the compartments and control means for said last mentioned means.

85 90 95 100 105 In testimony whereof I hereby affix my signature.

Mrs. ELSIE BROWN.
